J. WILCOX, JR

CLOCK CASING

Filed June 13, 1925

UNITED STATES PATENT OFFICE.

JOSEPH WILCOX, JR., OF ATHOL, MASSACHUSETTS, ASSIGNOR TO WILCOX NOVELTY COMPANY, OF ATHOL, MASSACHUSETTS, A CORPORATION OF MASSACHUSETTS.

CLOCK CASING.

Application filed June 13, 1925. Serial No. 36,984.

To all whom it may concern:

Be it known that I, JOSEPH WILCOX, Jr., a citizen of the United States, residing at Athol, in the county of Worcester and State of Massachusetts, have invented a new and useful Clock Casing, of which the following is a specification.

This invention relates to a casing for small clock movements and is preferably made of celluloid or other similar sheet material. In such casings the movements are commonly inserted from the back and are preferably retained by friction therein.

It is the object of my invention to provide an improved and simplified construction of casing for such purposes, in which the rear member or back of the casing is entirely omitted.

A further object is to provide a casing of a stronger and more rigid construction and one well adapted to artistic and ornamental development.

With these general objects in view, my invention relates more particularly to certain arrangements and combinations of parts which will be hereinafter described and more particularly pointed out in the appended claims.

A preferred form of the invention is shown in the drawings, in which—

Fig. 1 is a front elevation of a clock casing embodying my invention;

Fig. 2 is a side elevation thereof;

Fig. 3 is a partial rear view of the clock casing;

Fig. 4 is a sectional end elevation, taken along the line 4—4 in Fig. 1;

Figs. 5 and 6 are partial rear elevations, showing the adaptation of the casing to movements of different shapes; and

Fig. 7 is a partial end elevation, illustrating a further modification.

Referring to the drawings, I have shown a casing comprising a front member 10 and a base member 11 permanently secured together, with the member 11 projecting rearward from the member 10 and preferably at a right angle thereto. Legs or supports 12 may be provided for raising the base member 11 above the table or other surface on which the casing rests.

The front member 10 is provided with a movement opening 13 corresponding in general outline to the shape of the movement to be mounted in the casing. In Figs. 1 to 4

inclusive, I have shown a casing designed to receive a movement of the so-called gothic shape.

At the back of the member 10 I provide a casing support 15 preferably formed of a continuous strip of sheet material bent to closely engage the movement and having its end portions 16 united and extended downward to form a brace for the movement support. This depending portion 16 is preferably secured rigidly and permanently to the base member 11, thus holding the front member 10 and the base member 11 very firmly in their desired relative positions and also supporting the movement in fixed relation thereto.

The movement M is commonly provided on some portions of its outer surface with small projections 20, shown in Fig. 3 as formed by the heads of screws extending inward from the outside of the movement. These projections commonly engage the movement support 15 as the movement is fully inserted, pressing the walls of the support slightly outward from normal position and increasing the friction of the support upon the movement.

This additional friction is not particularly necessary with a movement of non-circular shape, such as is shown in Fig. 3, but is sometimes desirable where a circular movement is used, to prevent angular displacement thereof. In Fig. 5, I have indicated the movement support 22 as adapted to receive a circular movement, and in Fig. 6, the movement support 23 is adapted to receive a square movement.

In Fig. 7, I have shown a construction in which the casing comprises merely a face or front member 25 and a movement support 26 having a depending portion 27 directly engaging the surface on which the casing rests, with the base member 11 entirely omitted. This construction, while more cheaply and easily manufactured than the form shown in Figs. 1 and 2, nevertheless retains many of the advantages of my invention.

While my improved casing may be made of any suitable material, it is particularly well adapted for the use of celluloid or other similar flexible sheet material.

It will thus appear that I have provided a clock case of extremely simple construction, while at the same time the movement

is fully protected and the casing is firm and rigid and well adapted to the purposes for which it is designed.

Having thus described my invention and the advantages thereof, I do not wish to be limited to the details herein disclosed otherwise than as set forth in the claims, but what I claim is:—

1. A clock casing forming a permanent enclosure for a clock movement and comprising a front member, a base member fixed thereto, and a movement support firmly secured to said front member and also to the base member and forming a brace between said parts, said support being effective to frictionally retain a movement therein.
2. A clock casing forming a permanent enclosure for a clock movement and comprising a front member, a base member secured thereto and projecting rearwardly therefrom, and a movement support firmly secured to the rear face of said front member and having a depending portion engaging and firmly secured to said base member, said support being effective to frictionally retain a movement therein.
3. A clock casing forming a permanent enclosure for a clock movement and comprising a front member, a base member fixed thereto and a movement support formed of a single piece of sheet material, bent to

closely embrace a movement and having its end portions secured together and extending downward to form a brace for said parts and to firmly support said movement, said support being firmly secured to said front member and to said base member and being effective to frictionally retain a movement therein.

4. A clock casing having a front member, and a movement support secured to the back thereof, said support closely embracing said movement and having a depending portion forming a rearward brace for the front member and movement, and said support being effective to frictionally retain a movement therein.

5. A clock casing having a front member and a movement support secured to the back surface thereof, said support closely embracing said movement and having an integral depending portion forming a rearward brace for the front member and movement, said movement support being permanently and rigidly secured to the back face of said front member, and said support being effective to frictionally retain a movement therein.

In testimony whereof I have hereunto affixed my signature.

JOSEPH WILCOX, JR.
